TRAFFIC LIGHT

Kenneth E. Fenton, Pennville, and
Harry B. Smith, Upland, Ind.

Application October 21, 1935, Serial No. 45,880

3 Claims. (Cl. 177—327)

Our present invention relates to traffic lights which register the contemplated direction of the turning of a vehicle, the same being positively controlled by the driver of the vehicle.

5 An object of the invention is the provision of a direction signalling device to be attached to the rear end of an automobile or other similar vehicle.

Another object of the invention is the provision 10 of a traffic light or signalling device which will accurately indicate the contemplated direction of turning, which is simple of operation and construction, and which is economical to manufacture.

15 Other objects and advantages of the invention will suggest themselves in the course of the following description, and that which is new will be correlated in the appended claims.

The most satisfactory manner of carrying out 20 the principles of the invention in a practical, comprehensive, and efficient manner is shown in the accompanying sheet of drawings, in which:—

Figure 1 is a partial elevation of a mounting 25 panel with controlling switches mounted thereon.

Figure 2 is a detail section through the mounting panel, taken on line 2—2 of Figure 1.

Figure 3 is an elevation of the traffic light.

Figure 4 is a plan view of the traffic light, taken 30 from line 4—4 of Figure 3.

Figure 5 is a detail cross section through the device, taken on line 5—5 of Figure 4.

Figure 6 is a detail longitudinal section through the device, taken on line 6—6 of Figure 3.

35 Figure 7 is an elevation of the device, showing the same as indicating a left turn.

Figure 8 is an elevation of the device, showing the same as indicating a right turn.

Figure 9 is a detail elevation of the central di- 40 viding plate.

Figure 10 is an elevation of the device com- bined with a tail light.

Similar indices designate like parts throughout the several views.

45 In order that the construction, the operation, and the advantages of our invention may be more fully understood and appreciated, we will now take up a detailed description thereof, in which we will set forth the same as fully and as comprehensively as we may.

In the drawing, A designates the mounting or instrument panel through which the switches 1 and 2 are secured, the panel being preferably formed of sheet metal. The panel A has apertures formed therethrough for the reception of

the switches 1 and 2 which extend through the panel, the switches being rigidly secured therethrough by means of the threaded nuts 3 and 4 respectively. The switches 1 and 2 have the push stems 1' and 2' which are adapted to make contact when pushed inwardly, and to automatically break contact when the pressure is released therefrom, and thereby closing and opening an electrical circuit. The electric wire 5 is removably secured to the end portion of the switch 1 by 5 means of the threaded screw 7, and the wire 6 is removably secured to the end portion of the switch 2 by means of the threaded screw 8, as shown in Figure 2. The wires 27 and 28 are secured to the sides of the switches 1 and 2 by the 10 screws 29 and 30 respectively, as shown in Figure 2.

The traffic light, per se, is preferably formed of sheet metal, the same having the back 9, the top portion 9', the bottom portion 9'', and the left and right end portions 9^a and 9^b, all of which are formed integral with each other, thereby forming a metal box.

The mounting bracket 10 is rigidly secured to the back 9 and the bottom side 9'' by means of the vertically and horizontally extending legs 10' and 10'' respectively, the same being rigidly secured thereto by welding, or by other suitable means.

The angle stops 11 are rigidly secured to the top and bottom sides 9' and 9'' by welding, or other suitable means, and are used to form stops against which the glass 12 rests.

13 designates the metal cover of the traffic light, the same having all of its edges turned 35 at right angles with relation to the face or main portion thereof. 13' designates the aperture which is formed in the face of the cover 13, and which is substantially in the shape of a double-headed arrow, as shown in Figures 3 and 10, the same being for the purpose of allowing light to emanate through the exposed portion of the glass 12 whereby the contemplated direction of turning is indicated.

The cover 13 is removably secured to the end 45 portions 9^a and 9^b by means of the threaded screws 14 which extend into threaded apertures formed in the ends 9^a and 9^b.

15 designates the central dividing plate which is rigidly secured to the back 9 and the top and 50 bottom sides 9' and 9'' respectively by welding or other suitable means. An M-shaped notch 15' is formed in one edge of the dividing plate 15, the same being for the purpose of allowing light to pass therebeyond, with the edge of the 55

M-shaped notch 15' obstructing the light, and causing a shadow to be cast on a portion of the exposed glass area, as indicated by the lines X and Y of Figures 7 and 8 respectively.

5 Apertures are formed through the back member 9, through which the sockets 16 and 17 extend, the same being rigidly secured therein by welding or other well-known means. The electric bulbs 18 and 19 are removably secured in 10 their respective sockets 16 and 17 in the usual manner. The plugs 20 and 21 are removably secured in the opposite ends of the sockets 16 and 17 in the usual manner. The wires 5 and 6 are secured, at one of their ends, in their respective 15 plugs 20 and 21, and at their opposite ends to their respective switches 1 and 2.

The numeral 22 designates a tail light case which may, if desired, be formed integrally with the upper portion of the traffic light, thereby 20 forming a combination tail and traffic light. The numeral 23 designates the tail light lens, 24 designates the license plate bracket which extends upwardly from the tail light case 22, 25 designates a license plate carried by the bracket 24, and the numerals 26 designate bolts which rigidly 25 secure the license plate 23 to the bracket 24.

The operation of the traffic light is substantially as follows:

Electricity, for the operation of the traffic light, 30 is obtained from a storage battery which is in connection with the vehicle on which the traffic light is attached. One of the battery terminal posts is grounded to the frame of the vehicle in the usual manner with the other terminal being 35 connected to the switches 1 and 2 by means of the wires 27 and 28 respectively. The traffic light is rigidly secured, through the bracket 10, to a frame member of the vehicle.

When it is desired to indicate a contemplated 40 left turn, the push stem 1' is pushed inwardly and causing its inner end to contact the inner end of the screw 7, thereby closing the circuit from the battery terminal through the wire 27, the switch 1, the wire 5 to the bulb 18 and grounded 45 through the socket 16, the case 9, the bracket 10, thence through the frame to which the grounded terminal of the battery is connected, thereby completing the circuit and causing the filament 18' to glow, the same providing light 50 which emanates through the glass 12 and through the aperture 13' of the cover 13, as shown in Figure 7.

It will be noted, by Figure 7, that the right end of the arrow is not lighted by the bulb 18 due to the M-shaped notch 15', of the central 55 dividing plate 15, the edges of which obstruct a portion of the light emanating therefrom, and casting a shadow on the glass 12, thereby causing the arrow to appear as having only one head with the same pointing toward the left.

60 When it is desired to indicate a contemplated right turn, the push stem 2' is pushed inwardly and causing its inner end to contact the inner end of the screw 8, thereby closing the circuit from the battery terminal through the wire 28, the switch 2, the wire 6 to the bulb 19 and grounded 65 through the socket 17, the case 9, the bracket 10, thence through the frame to which the grounded terminal of the battery is connected, thereby completing the circuit and causing the filament 19' to glow, the same providing light 70 which emanates through the glass 12 and through the aperture 13' of the cover 13, as shown in Figure 8.

It will be noted, by Figure 8, that the left end of the arrow is not lighted by the bulb 19 due to the M-shaped notch 15', of the central dividing plate 15, the edges of which obstruct a portion of the light emanating therefrom, and casting a shadow on the glass 12, thereby causing the arrow to appear as having only one head with the same pointing to the right.

5 In order to break either of the two circuits, it is only necessary to release the pressure on the 10 push stem, which automatically breaks the respective electrical circuit.

It is to be understood that the switches and traffic light may be directly connected to the storage battery by means of two wires instead of the 15 above-described one-wire circuit, and to obtain the same results thereby.

It is also to be understood that minor changes may be made in the several parts and in the arrangement thereof without departing from the 20 spirit of the invention or sacrificing any of the advantages thereof.

Having now fully described the invention and the parts thereof, what we desire to secure by Letters Patent of the United States, is:

25 1. In a directional traffic light, the combination of a case, a cover for said case, said cover having an elongated aperture formed in the face portion thereof, a glass lens securely positioned in said case by means of said cover, a bracket 30 rigidly secured to and carrying said case, a single centrally located flat dividing plate rigidly secured in said case and dividing the same into two separate compartments, said dividing plate having an M-shaped notch formed in one edge 35 thereof with the base of the M positioned adjacent the glass lens and adapted to cast a V-shaped shadow on the glass lens, an electric light bulb removably secured in each of said compartments, and means for completing an electrical circuit through each of said bulbs independently of the other.

40 2. A directional traffic light having in combination, a case having a back, top and bottom sides, and ends, a single centrally located flat dividing 45 plate rigidly secured in said case, the same having an M-shaped notch formed in one edge thereof, a glass lens closing the open side of said case and contacting the base of the M-shaped notch of the dividing plate, a cover removably secured 50 to said case and retaining the glass in position, said cover having an elongated aperture formed through the face portion thereof with the outline of an arrow head formed at each end of the elongated aperture, and means for producing 55 light within said case and indicating the direction of a contemplated turn by light emanating through the glass lens and the elongated aperture formed in the cover.

60 3. In a traffic light comprising a case having a glass lens positioned in one side thereof, a cover having an elongated aperture formed therethrough with the outline of an arrow head formed at each end thereof and forming a part of the elongated aperture, a single flat dividing plate 65 having an M-shaped notch formed in the edge nearest the glass lens with the base of the M-shaped notch positioned adjacent the glass lens, said dividing plate being rigidly secured substantially midway between the ends of said case, and means for producing light within said case, all substantially as shown and described.

KENNETH E. FENTON.
HARRY B. SMITH.
